CLAIM

The ornamental design for a nightstand, as shown and described.

DESCRIPTION

FIG. 1 is a perspective view of a nightstand in accordance with my invention;

FIG. 2 is a front elevation view of the nightstand shown in FIG. 1;

FIG. 3 is a rear elevation view of the nightstand shown in FIG. 1;

FIG. 4 is a right side elevation view of the nightstand shown in FIG. 1; and

FIG. 5 is a left side elevation view of the nightstand shown in FIG. 1; and,

FIG. 6 is a top plan view of the nightstand shown in FIG. 1. The bottom side of the nightstand is unadorned.
